CHURN FOR THE PRODUCTION OF VISCOSE

William R. Weigham, Coventry, and William H. Stokes, Balsall Common, near Coventry, England, assignors to Courtaulds Limited, London, England, a British company

Application September 17, 1951, Serial No. 246,942
In Great Britain October 11, 1950

2 Claims. (Cl. 259—3)

1

This invention relates to churning for use in the production of viscose.

Customary steps in the production of viscose include the treatment of alkali cellulose with carbon disulphide to produce cellulose xanthate and the dissolution of the cellulose xanthate in dilute alkali to form the viscose. The carbon disulphide provides serious fire and health hazards against which stringent precautions are taken. One well known method involves mixing the alkali cellulose with carbon disulphide in a hermetically sealed rotating churn (a so-called "dry churn") from which the dry cellulose xanthate is removed and passed to a separate mixer in which the dissolution in dilute alkali is effected. One drawback of this process is that the churn has to be cleaned out after each xanthation; normally the cleaning is carried out by an operative brushing and scraping the inside of the churn. By another known method the two steps of xanthation and dissolution are effected consecutively in a single sealed churn (a so-called "wet churn") the dilute alkali being admitted on the completion of the xanthation. This second method has the advantage of facilitating the clearance of the churn, but on the other hand it involves the use of considerably more power than the first method as it is normally carried out in a fixed churn with stirring paddles rotated slowly during the xanthation stage and more rapidly after the admission of the dilute alkali. In addition the fire hazard within the churn is greater due to the moving parts.

It is the object of the present invention to obtain the advantages of the second method without its main disadvantages.

According to the present invention a churn for the production of viscose comprising a shaft, a container mounted on said shaft and stirring mechanism also mounted on said shaft and extending within the container over at least half of the internal capacity of the container, is provided with the combination of locking mechanism whereby, when the container is rotated, the stirring mechanism is also rotated so that there is no relative motion between the container and the stirring mechanism, and free-wheel mechanism whereby the stirring mechanism can be rotated relative to the container. The container is preferably surrounded by a jacket so that the contents of the churn may be heated or cooled as desired.

In the preferred method of operating the churn according to the invention the container is charged with alkali cellulose, sealed, evacuated and then rotated with the stirring mechanism locked relative to the container whilst the carbon disulphide is admitted and the xanthation effected; the container is then stopped, dilute alkali is admitted and the stirring mechanism is set in motion relative to the container to effect dissolution; the solution is then removed and the churn washed out with further dilute alkali

2

which is added to the viscose solution removed from the churn. Before re-charging with alkali cellulose the churn is preferably washed with caustic soda of approximately mercerising strength to avoid wetting of the alkali cellulose.

5 A specific example of a churn constructed in accordance with the present invention is illustrated in the accompanying drawings, in which

Fig. 1 is a front elevation partly in section;

Fig. 2 is a section through the free wheel mechanism of Fig. 1; and

Fig. 3 is a rear elevation of part of Fig. 1.

A churn indicated generally at 1 comprises a container 2 surrounded by a jacket 3. The churn 1 has a free wheel 4 at one end and a hollow shaft 5 at the other end. A shaft 6, held in two bearings 7, 8 in frames 9, 10 respectively, protrudes through the free wheel 4 into the container 2 and the shaft 5 is held in a bearing 11 in a third frame 12 so that the churn 1 is capable of rotation about its horizontal axis.

15 A paddle 13 is mounted at the end of the shaft 6 within the container 2 and may be rotated by a pulley 14 splined to the shaft 6. The pulley 14 is capable of being driven from an overhead drive (not shown) through a driving belt 15, which is shifted off an idler pulley 25 by a belt shifting fork 16 when required.

20 The churn 1 may be rotated by shifting the belt 15 by means of the belt-shifting fork 16 on to a third pulley 17 mounted on a sleeve 18 surrounding the left-hand end of the shaft 6. A gear-wheel 19, also mounted on the sleeve 18, drives the free wheel 4 through a reduction gear chain 20 and an idler gear-wheel 21.

25 Referring to Fig. 2, the shaft 6 having a collar 50 splined to it passes through a ring 51 fixed centrally to the free wheel 4. Four slots 52 are cut in the internal surface of the ring 51 which lies in contact with the collar 50, thus defining four passages 53 which are parallel to the shaft 6. Each passage 53 encloses a roller 54 lying parallel to the shaft 6 and is tapered in a clockwise direction about the axis of the shaft 6 so that its maximum width is greater and its minimum width smaller than the diameter of each roller 54.

30 Each roller 54 is spring pressed by means of a spring 55, enclosed by a cap 56, into the tapered part of each passage 53, so that it is in contact with both the ring 51 and the collar 50. The spring 55 is housed in a bore 57 opening into the wider part of each passage 53 and is held in position by a screw 58.

35 During the xanthation stage, the free wheel 4 is rotated in an anticlockwise direction and the rollers 54 are forced into the tapered parts of the passages 53 by the action of the rotation. The rollers 54 act as wedges and the collar 50 is

40 locked to the ring 51 so that the collar 50 together with the shaft 6 are made to rotate with the free wheel 4. Consequently, the paddle 13

is locked to the churn 1 and is caused to rotate with the churn 1.

During the dissolution stage, the shaft 6 together with its associated collar 50 is rotated in a clockwise direction by the pulley 14. The rollers 54 now tend to move out of the tapered parts of the passages 53 against the action of the springs 55 to a position where the width of the passages 53 is greater than the diameter of the rollers 54. Consequently there is no driving contact between the collar 50 and the ring 51, and the collar 50 rotates freely within the ring 51, that is, a "free wheeling effect" is obtained and the free wheel 4 receives no drive. When the rotation of the collar 50 stops, the rollers 54 are again urged into the tapered parts of the passages 53 by the springs 55.

To prevent the churn "creeping" during the dissolution stage, a brake 22 is applied when shifting the driving belt 15 on to the pulley 14 by means of the belt shifting fork 16.

As shown in Fig. 3, the fork 16 is mounted on a screw 60 which is rotatable by a handle 61. A cam 62 is fixed to the lower side of the fork 16 and is free to slide in a slot 63 in the frame 9 as the fork 16 is moved along the screw 60 by the rotation of the handle 61. A cam follower 64 mounted on one end of an arm 65 rides against the cam 62. The arm 65 is attached, at its other end, to a cam member (not shown) which is capable of expanding a brake band 66 against the internal surface of a brake drum 67 of the brake 22. Normally, the band 66 is held in a contracted state out of contact with the drum 67 by means of a spring (not shown) within the brake 22. The cam 62 is so shaped that when the belt 15 is driving the pulley 17 or rotating the idler pulley 25 the brake 22 is inoperative, but when the belt 15 is moved on to the pulley 14, the cam follower 64 is pressed down against the spring within the brake 22 and the brake 22 is operated, thus preventing the sleeve 18, and consequently the churn 1, from rotating. The brake 22 may also be operated by a foot-pedal 23 through a rod 68 connecting the pedal 23 and the arm 65. A hand-wheel 24 is fitted to the end of the sleeve 18 for manual rotation of the churn during loading operations.

In a typical churning operation in the manufacture of viscose, alkali cellulose crumbs are charged into the churn 1 through a charging door 26 from a chute 21. The door 26 is then closed and air is evacuated from the container 2 through a pipe 28 passing through the centre of the shaft 5, communicating with a chamber 29 in a column 30 having an opening 31.

Carbon disulphide, delivered to the container 2 by means of a second pipe 32, is now passed through the pipe 28 and through a second chamber 33 in the column 30 to a nozzle 34.

When the churn contains the alkali cellulose and the carbon disulphide the driving belt 15 is shifted from the pulley 25 on to the pulley 17 so that the churn 1 and the paddle 13 are rotated for the duration of the xanthation period. The belt 15 is then shifted back to the pulley 25 and the churn 1 braked by the brake pedal 23.

A quantity of dilute aqueous sodium hydroxide solution rather less than the total volume ultimately required is now admitted to the container 2 through a third pipe 35 passing through the pipe 28, to the chamber 33 and the nozzle 34. The belt 15 is then shifted on to the pulley 14 and the paddle 13 rotated while the churn 1 is held stationary by the brake 22.

When the cellulose xanthate has been dissolved, the belt 15 is shifted back on to the pulley 25 and the churn 1 rotated by means of the hand-wheel 24, until the door 26 is positioned over a discharge chute 36 in the churn room floor 37. The door 26 is removed and the solution discharged into the chute 36. The remainder of the dilute sodium hydroxide solution is now passed into the churn 1 through the nozzle 34 to wash out the residual cellulose xanthate solution and this also passes down the chute 36. The churn 1 is now ready for the cycle to be repeated.

The temperature of the container 2 is controlled by passing a heated fluid continually into a space 38 between the container 2 and the jacket 3 by means of an inlet pipe 39 communicating with an internal pipe 40 within the wall 41 of the hollow shaft 5 which opens into the space 38. The fluid passes out of the space 38 by a second internal pipe 42 communicating with an outlet pipe 43.

If desired the churn can be modified to permit a continuous supply of carbon disulphide in a manner similar to that adopted with known "wet churning" but this requires more complex packing glands.

A churn constructed in accordance with the invention requires small power only to rotate it during the xanthation and the fire hazard is low owing to the absence of parts moving relatively to one another.

What we claim is:

1. A churn for the production of viscose comprising in combination, a container, a free wheel secured to the container, a driving shaft passing through the free wheel, extending into one end of the container and supporting the container, a stirring mechanism mounted on the driving shaft within the container, said mechanism extending over at least half of the internal capacity of the container, a hollow shaft passing into the other end of the container for introducing fluids into the container co-aligned with the driving shaft and also supporting the container, a support for the driving shaft, a second support for the hollow shaft, two independent driving wheels mounted on the driving shaft, one of the said driving wheels being freely mounted on the driving shaft and geared to the free wheel so that when a drive is directed to the said driving wheel the container and the stirring mechanism are locked and rotated together so that there is no relative motion between the container and the stirring mechanism and when the drive is directed to the second driving wheel which is fixed to the driving shaft, the stirring mechanism is rotated while the container remains substantially stationary.

2. A churn as claimed in claim 1 wherein there is a jacket surrounding the container so that the temperature of the contents may be controlled by a fluid circulating in the jacket, and a pipe accommodated within the hollow shaft to pass to the fluid.
